UNITED STATES PATENT OFFICE.

HARRY C. RUSH, OF DAWSON, PENNSYLVANIA, ASSIGNOR OF ONE-HALF
TO JAMES S. LAUGHREY, OF DAWSON, PENNSYLVANIA.

RAILWAY-SWITCH.

No. 800,403.

Specification of Letters Patent.

Patented Sept. 26, 1905.

Application filed November 11, 1904. Serial No. 232,591.

To all whom it may concern:

Be it known that I, HARRY C. RUSH, a citizen of the United States, residing at Dawson, in the county of Fayette and State of Pennsylvania, have invented a new and useful Railway-Switch, of which the following is a specification.

The invention relates to improvements in railway-switches.

10. The object of the present invention is to improve the construction of railway-switches and to provide a simple and comparatively inexpensive one designed for use on all kinds of railways and adapted particularly for use on those railways employing the third-rail system and capable of operation either by hand or by a locomotive, motor-car, or other car or motor equipped with the switch-operating devices.
20. A further object of the invention is to provide an automatic lock capable of securely holding the movable switch-rails and a movable third-rail section to prevent any accidental movement of the parts and adapted to release the parts prior to an operation of the switch and to relock the parts as soon as the switch has been operated.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

40. In the drawings, Figure 1 is a perspective view of a railway-switch constructed in accordance with this invention. Fig. 2 is a plan view, the cover or hinged top of the box or casing being removed. Fig. 3 is a longitudinal sectional view on the line 3 3 of Fig. 2. Fig. 4 is a transverse sectional view on the line 4 4 of Fig. 2. Fig. 5 is a transverse sectional view on the line 5 5 of Fig. 2. Fig. 6 is a detail perspective view illustrating the construction of the switch-operating arm and the latch-releasing arm. Fig. 7 is a detail perspective view illustrating the construction of the latch mechanism. Fig. 8 is a similar view illustrating the construction for operat-

ing the switch and the latch by hand. Fig. 9 is a side elevation of a portion of a locomotive, illustrating the arrangement of the switch-operating devices. Fig. 10 is an end elevation of the same. Fig. 11 is a side elevation illustrating the manner of mounting the switch-operating mechanism on the tender of a locomotive.

Like numerals of reference designate corresponding parts in all the figures of the drawings.

1 and 2 designate pivoted switch-rails, and 3 designates a pivoted third-rail section, the switch in the accompanying drawings being shown applied to an electric railway operated by the third-rail system and having a third rail 4 of the ordinary construction.

Although in the accompanying drawings the switch is shown applied to a railway operated by the third-rail system, such as is used in or about mines, yet it will be readily understood that the present invention may be applied to any other railway, whether steam, electric, or other motive power be employed for operating the cars or trains. The movable third-rail section 3 is pivoted at 5 and 6 consists of a bed-plate or base provided with a straight-rail section 6 and a curved-rail section 7. The straight-rail section is adapted to form a continuation of the third rail 4 of the main line, and the curved third-rail section 8 is adapted to form a continuation of the third rail 8 of the branch road 9.

The movable switch-rails, which are pivoted at 10 and 11, are connected by a transverse rod or bar, which causes the switch-rails to move in unison. The switch-rail 1 is yieldably connected with one arm of a bell-crank lever 12, the yieldable connection 13 being adapted to permit a train approaching the switch from the branch line to move the switch-rails 1 and 2 and enter the main line. After such train has passed the spring 14 of the yieldable connection will automatically close the switch. The other arm of the bell-crank lever 12 is connected with a reciprocating bar 15, located at one side of the track, as clearly shown in Fig. 2 of the drawings. The arm of the bell-crank lever which is connected with the switch-rails extends longitudinally of the track and the arm which is disposed transversely thereof is provided with a notch 16 for the reception of a pin 17 of a bracket 18, which is secured to the bar 15.

The bracket consists of a plate fitted against one end of the bar 15 and a centrally-arranged projecting portion from which depends the pin which operates in the notch or recess of the bell-crank lever. By this construction the parts are pivotally connected and the necessary play incident to the longitudinal movement of the bar 15 and the oscillatory movement of the bell-crank lever is 5 permitted. The bar 15, which has a limited reciprocation, is provided with central and end slots 19, through which pass fastening devices 20 for securing the reciprocating bar to its supports. These supports preferably consist of extensions of the adjacent cross-ties.

The movable third-rail section is connected by a transverse bar 21 with a longitudinal arm of a bell-crank lever 22, which is fulcrumed at its angle and which has its other arm disposed transversely and notched to receive a pivot-pin 23 of a bracket 24. The bracket 24 is of the same construction as that heretofore described, and when the bar 15 is reciprocated motion will be communicated to the 25 bell-crank levers and the switch-rails and the movable third-rail section will be operated.

The reciprocating bar is actuated to operate the switch-rails by a pair of switch-operating arms 25 and 26, arranged to the right 30 and left hand sides of the track and mounted on rock-shafts 27 and 28, which are provided with oppositely-disposed arms 29 and 30. The shaft 28 is tubular and is arranged on the shaft 27, and the arms 29 and 30 are connected by rods or bars 31 and 32 with the reciprocating bar. The rock-shafts are journaled in suitable bearings, and the switch-operating arms, which are movable in opposite directions, are provided with inclined upper faces adapted to be engaged by switch-operating devices, hereinafter explained. When one of the switch-operating arms is depressed by the means hereinafter described, the other switch-operating arm will be elevated. The 40 switch-operating arm 25 at the right-hand side of the track is depressed to open the switch and the downward movement of the said switch-operating arm 25 swings the depending arm 29 of the rock-shaft 27 in the direction of the arrow in Fig. 3 and operates the switch-rails. The downward movement of the other switch-operating arm 26 moves the reciprocating bar in the opposite direction and closes the switch. The movable third-rail 45 section is operated simultaneously with the switch-rails through its connections with the bar 15, as will be readily understood.

The switch-operating arms are provided at their upper faces with recesses 33, adapted to 50 receive latch-releasing arms 34, which are located normally above the switch-operating arms and which are adapted to be operated prior to the operation of the arms 25 and 26 in order to unlock the movable switch-rails 55 and the movable third-rail section. As soon

as the operating devices, hereinafter described, has depressed the switch-operating arm and releases the arm 34 the latter will automatically resume its normal position, as hereinafter explained, and the movable switch-rails and 70 the movable third-rail section will be locked in their adjusted and shifted positions. The arms 34 are suitably fixed to a transverse rock-shaft 35, which is journaled in suitable bearings and which is provided with an upwardly-extending arm 36. The arm 36 is pivotally connected with one end of a rod 37, which extends longitudinally of the track at one side thereof to a latch 38. The latch 38, which is L-shaped and which is pivoted at its angle by 80 a pin 39 to a bracket 40, is located at one side of the track opposite the movable third-rail section and is adapted to engage a slide 41, that is connected with the said third-rail section. Although the latch mechanism is shown connected with the movable third-rail section when the switch is applied to a railway having a third-rail system, yet it will be readily understood that when the third-rail system is not employed the latch may be connected with 85 one of the movable switch-rails. The slide, which is arranged horizontally, is provided at its upper edges with notches 42 and 43 and adapted to receive the latch, whereby the slide is locked against reciprocation. The slide, 90 which is provided with a longitudinal slot 44, is mounted on a guide 45, consisting of a horizontal plate having an upwardly-extending portion or piece 46. The guide is provided with a horizontal upper edge to receive the 100 slide and the upwardly-extending portion or piece 46 is provided with a block 47, which is arranged in the slot of the slide. One end of the slide is provided with a perforated flange and is connected by a pivot 48 with 105 the outer end of a transverse rod or bar 49. The rod or bar 49 extends to and is pivotally connected with the movable third-rail section, whereby when the latter is oscillated the slide will be reciprocated. When the latch is in 110 engagement with one of the notches of the slide, the movable switch-rails and the pivoted third-rail section will be positively locked against accidental movement. The engaging arm or portion of the L-shaped latch is horizontal, and the other arm, which is vertical, is connected to the adjacent end of the rod 37, which is provided at its ends with substantially U-shaped straps or pieces for the reception of the arm 36 of the rock-shaft 35 and 115 the upwardly-extending arm of the latch. The upwardly-extending arm of the latch is provided with a series of perforations to enable it to be adjusted, and the arms 29 and 30 are also provided with perforations for 120 adjusting the connecting-bars 32 and 31. Various other parts of the switch may be provided with similar means for adjustment, and the rod 37 is composed of two sections 125 adjustably connected by a coupling-sleeve 50, 130

having clamping-screws 51 for engaging the sections of the rod. The latch is normally held in its engaging position by means of a coiled spring 52, disposed on the rod and interposed between an adjustable collar 53 and a guide or bracket 54. The guide or bracket 54, which is L-shaped, is provided in one of its arms with an opening through which the rod 37 passes.

10 The bar 15 has secured to it a plate 55, which is provided with a flange 56, having a plurality of notches 57, one of which is engaged by an operating-lever 58. The operating-lever 58, which is L-shaped, is fulcrumed at its angle, and it consists of a short transverse arm and a long longitudinal arm. The transverse arm extends into one of the notches 57, and the longitudinal arm, which is provided with a suitable grip or handle, is arranged in a horizontal slot 59 of a guide 60, which is also provided with a vertical slot 61, having a shoulder at its upper portion and receiving a lever 62. The lever 62, which is fulcrumed on a bracket 63, is provided with a laterally-projecting pin 64, arranged to engage the arm 36 for swinging the latch upward out of engagement with the slide when it is desired to operate the switch by hand through the lever 58. In practice when the switch is employed 20 at a mine the space between the rails of the track will be covered from the switch-operating arms to the movable third-rail section and the mechanism at the side of the track will be arranged in a box or casing 65. The 25 box or casing 65 is provided with a hinged cover, which is secured in its closed position by suitable catches 66.

The switch-operating devices for engaging the arms 25 and 26 and the latch-releasing 30 arms consist of resilient plates or bars 67, arranged in pairs at opposite sides of the locomotive, motor-car, or other car to which they are applied. The members of each pair of plates or bars are fixed at their outer ends 68 and have their inner ends 69 curved upwardly and pivoted to the lower ends of a pair of links 70. The upper ends of the links are connected to a lever 71, fulcrumed at one end and connected at the other end by suitable 35 operating mechanism. When the resilient bars or plates are in an inoperative position, they are substantially horizontal, and when it is desired to set them for operating the switch they are flexed and bent downward and presented oppositely-inclined faces to the switch-operating arms. The levers 71 are locked against upward movement by keepers 72, having engaging shoulders and provided above the same with beveled faces. In order to permit only one pair of the operating devices to be set at the same time, a slideable tripping device 73 is provided. The tripping device, which consists of a plate or bar, extends from one keeper to the other, and when one of the 40 levers is in engagement with its keepers the

tripping device extends therefrom to a point beyond the shoulder of the other keeper, whereby when the other lever is moved downward into engagement with its keeper the tripping device will be reciprocated and will release the first-mentioned lever, which will be raised by the resilient plates or bars 67 or by the operating mechanism.

In Fig. 11 of the drawings is illustrated a switch-operating device composed of a pair of bars 74, pivoted at their outer ends to suitable hangers 75 and connected at their inner ends by links 76 with the piston 77 of a cylinder 78. This switch-operating device is designed to be located beneath the tender of a locomotive; but it may be readily mounted on a street-car or motor and the piston of the cylinder may be operated by compressed air or any other suitable means. When the switch-operating bars 74 are swung downward, as illustrated in dotted lines in Fig. 11, they are adapted to operate the switch-operating arms and the latch-releasing arms.

Having thus fully described my invention, what I claim as new, and desire to secure by Letters Patent, is—

1. In a railway-switch, the combination with movable switch-rails, of switch-operating arms, rock-shafts connected with the arms and provided with oppositely-disposed arms, and means for connecting each of the latter with the movable switch-rails.

2. In a railway-switch, the combination with movable switch-rails, of rock-shafts provided with oppositely-disposed arms, one of the rock-shafts being tubular and arranged on the other, means for connecting the said arms with the switch-rails, and switch-operating arms connected with the rock-shafts.

3. In a railway-switch, the combination with movable switch-rails, a reciprocatory bar, means for connecting the bar with the switch-rails, rock-shafts having oppositely-disposed arms connected with the reciprocatory bar, and switch-operating arms connected with the rock-shafts.

4. In a railway-switch, the combination with switch-rails, of a reciprocatory bar, a bell-crank lever fulcrumed at its angle and connected with the bar and with the switch-rails, rock-shafts having oppositely-disposed arms connected with the said bar, and switch-operating arms connected with the rock-shafts.

5. In a railway-switch, the combination with switch-rails, of a longitudinally-disposed reciprocatory bar, a bracket mounted on the bar and having a projecting portion, a pivot-pin carried by the projecting portion, a bell-crank lever provided at one end with a notch receiving the said pivot-pin, means for connecting the other end of the lever with the switch-rails, rock-shafts having oppositely-disposed arms connected with the said bar, and switch-operating arms connected with the rock-shafts.

6. In a railway-switch, the combination of a reciprocatory bar, rock-shafts having oppositely-disposed arms extending above and below the bar and connected with the same, one of the rock-shafts being tubular and arranged on the other, and switch-operating arms connected with the rock-shafts. 5
7. In a railway-switch, the combination with movable switch-rails, and a movable third-rail section, of a reciprocatory bar extending longitudinally of the track, means located at one end of the bar for connecting the same with the third-rail section, separate connecting means located between the ends of the bar for connecting the same with the switch-rails, and means connected with the other end of the bar for moving the same in either direction. 10
8. In a railway-switch, the combination with a movable third-rail section, of a reciprocatory bar, a bell-crank lever connected with the reciprocatory bar and with the third-rail section, rock-shafts having arms extending in opposite directions from the rock-shafts and connected with the bar, and operating-arms connected with the rock-shafts. 15
9. In a railway-switch, the combination of a reciprocatory bar, a bracket mounted on the bar and provided with a projecting portion having a pivot-pin, a bell-crank lever provided at one arm with a notch receiving the pivot-pin, means for connecting the other arm of the bell-crank lever with the part to be actuated, rock-shafts having arms connected with the bar, and means for operating the rock-shafts. 20
10. In a railway-switch, the combination with movable switch-rails, and a movable third-rail section carrying straight and curved rail-sections, of a reciprocatory bar, bell-crank levers connected with the bar, means for connecting one of the bell-crank levers with the switch-rails, and the other bell-crank lever with the movable third-rail section, and means for actuating the reciprocatory bar. 25
11. In a railway-switch, the combination with movable switch-rails, and a movable third-rail section, of a reciprocatory bar, means for guiding the same, bell-crank levers connected with the bar at one end of the same and at a point between the ends thereof, means for connecting one of the bell-crank levers with the switch-rails, and the other bell-crank lever with the movable third-rail section, and a lever for actuating the reciprocatory bar. 30
12. In a railway-switch, the combination of a movable switch-rail, a latch for locking the movable switch-rail, and operating mechanism connected respectively with the movable switch-rail and with the latch, and provided with arms arranged to be successively operated by the same device. 35
13. In a railway-switch, the combination of a movable switch-rail, a latch for locking the movable switch-rail, and operating mechanism connected respectively with the movable switch-rail and with the latch, and provided with arms overlapping and arranged one above the other in position to be successively operated by the same device. 40
14. In a railway-switch, the combination of a movable switch-rail, a latch for locking the movable switch-rail, and operating mechanism connected respectively with the movable switch-rail and with the latch, and provided with inclined overlapping arms arranged to be successively operated by the device, one of the arms being provided with a recess to receive the other. 45
15. In a railway-switch, the combination of a movable switch-rail, and operating mechanism embodying rock-shafts connected with the switch-rail, and provided with operating-arms extending from the rock-shafts in the same direction and movable in the opposite direction. 50
16. In a railway-switch, the combination with switch-operating mechanism embodying a switch-operating arm, a latch for the said mechanism, means for normally holding the latch in its engaging position, a rock-shaft connected with the latch, and a latch-releasing arm connected with the rock-shaft and arranged adjacent to the switch-operating arm said arms being arranged to be successively operated by the same device. 55
17. In a railway-switch, the combination with switch-operating mechanism embodying a switch-operating arm having a recess, a latch for the said operating mechanism, means for holding the latch normally in its engaging position, a rock-shaft connected with the latch, and a latch-releasing arm connected with the rock-shaft and arranged to be depressed into the recess of the switch-operating arm. 60
18. In a railway-switch, the combination with a movable switch-rail, of a latch for locking the same, switch-operating mechanism embodying rock-shafts provided with arms extending from the shafts in the same direction and movable in the opposite direction, and operating mechanism provided with operating-arms overlapping the arms of the switch-operating mechanism, each pair of arms being arranged to be successively operated by a single device. 65
19. In a railway-switch, the combination with switch-operating mechanism, of a latch therefor, a rock-shaft having an arm, a rod connecting the arm with the latch and composed of sections adjustably connected, a bracket for guiding the rod, a coiled spring disposed on the rod and engaging the bracket for actuating the said rod, and means for operating the rock-shaft. 70
20. The combination with a switch, and means for operating the same, of a slide, means for connecting the slide with the switch, 75

- a latch arranged to engage the slide for locking the switch against movement, and means for operating the latch.
21. The combination with a switch, and means for operating the same, of a latch for locking the switch, a slide connected with the switch and arranged to be engaged by a latch, a guide receiving the slide, and means for operating the latch.
22. The combination with a switch, and means for operating the same, of a slide having a slot, a guide receiving the slide and provided with a projecting portion having a block fitting in the slot of the slide, means for connecting the slide with the switch, a latch for engaging the slide to lock the switch, and means for operating the latch.
23. In a switch, the combination with movable switch-rails, of a reciprocating bar, means for guiding the same, means for communicating motion from the bar to the switch-rails, a latch for locking the switch-rails against movement, hand-operated means for releasing the latch, means for actuating the reciprocating bar by hand and train-actuated means for reciprocating the bar independently of the means for actuating the same by hand.
24. The combination with a switch, and means for operating the same by hand, of a latch for locking the switch, a latch-releasing lever, and means connected with the latch and arranged in the path of the lever for enabling the latter to operate the latch.
25. In a switch, the combination with movable switch-rails, and a movable third-rail section, of a rock-shaft having oppositely-disposed arms, means for communicating motion from the said arms to the movable switch-rails and the movable third-rail section, a latch for locking the switch-rails and the movable third-rail section, switch-operating arms connected with the rock-shaft, a rock-shaft connected with the latch and provided with latch-releasing arms located above the switch-operating arms, and means for holding the latch normally in its engaging position.
26. The combination with a switch, and operating mechanism embodying switch-operating arms, of operating devices designed to be mounted on a locomotive, car or the like and consisting of resilient plates or bars, and means for setting the plates or bars at an inclination and in position for engaging the said arms.
27. The combination with a switch, and switch-actuating mechanism, of opposite switch-operating devices, levers connected therewith, keepers arranged in the paths of the levers, and a tripping device arranged to be engaged by either of the levers for throwing the other out of engagement with its keeper.
28. The combination with a switch and means for actuating the same, of switch-operating devices, levers connected with the devices, keepers arranged in the paths of the levers, a reciprocating tripping device arranged at the keepers and adapted when actuated by one of the levers to disengage the other lever from its keeper.
29. The combination with a switch and means for actuating the same, of switch-operating devices consisting of resilient plates or bars arranged in pairs, levers, links connecting the levers with the resilient plates or bars, keepers arranged in the paths of the levers, and a tripping device arranged to be operated by either of the levers for disengaging the other lever from its keeper.
30. The combination with a switch, and operating mechanism embodying a switch-operating arm, of operating devices designed to be mounted on a locomotive, car, or the like, and consisting of a pair of bars disposed longitudinally, and means connected with the adjacent ends of the bars for swinging the same downward to an inclined position for operating the said arm.

In testimony that I claim the foregoing as my own I have hereto affixed my signature in the presence of two witnesses.

HARRY C. RUSH.
